UNITED STATES PATENT OFFICE

FREDERICK J. SÉVIGNE, OF MILFORD, NEW HAMPSHIRE, ASSIGNOR TO F. J. SEVIGNE MACHINE COMPANY, OF NASHUA, NEW HAMPSHIRE, A CORPORATION OF NEW HAMPSHIRE

MACHINE FOR MARKING ROUND ARTICLES

Application filed May 18, 1929. Serial No. 364,285.

This invention relates to the treatment of substantially spherical articles such as oranges and grape-fruit, so as to mark their surfaces with identifying trade-marks, names 5 or words.

In order to provide a satisfactory machine for printing or branding citrus fruits, it is necessary to meet and overcome certain difficulties arising from the fact that such articles vary greatly as to size and also, to a considerable extent, as to shape. Some are 10 much rounder than others.

In a general aspect, the present machine may be said to be of the type illustrated in 15 Letters Patent No. 1,501,817, granted to me July 15, 1924.

One of the objects of the present invention is to provide the machine with improved mechanism for conveying the articles to and 20 past the marking mechanism, with no stops during transit, thereby effecting a very high speed in the production of marked articles.

Another object is to provide a marking machine capable of operating on a wide range 25 of sizes of articles such as oranges and grape-fruit, even when the articles are supplied to the machine in mixed condition as to sizes.

With the above and other objects herein- 30 after referred to, my invention consists in the apparatus or machine substantially as hereinafter described and claimed.

Of the accompanying drawings:

Figure 1 is a perspective view of the machine in one of its embodiments.

Figure 2 represents a longitudinal section 35 of the machine.

Figure 3 is a detail perspective view of a portion of one of the marking wheels.

Figure 4 is a view similar to a portion of 40 Figure 2, illustrating the operation on citrus fruit.

Figure 5 represents a section on line 5—5 of Figure 2.

Figure 6 represents a section on line 6—6 45 of Figure 2.

Figure 7 is a detail elevation of a portion of the machine, looking in the direction of the arrow 7, Figure 2.

Figure 8 is a detail view of the parts at 50 the left of Figure 7.

Figure 9 represents a section on line 9—9 of Figure 8, on a larger scale.

Similar reference characters designate similar parts or features in all of the views.

The frame of the machine may be of any 55 suitable construction. The lower portions thereof are illustrated at 12, with uprights 13.

A motor 14 has its shaft connected by a belt 15 with the pulley 16 of a shaft 17 mounted in the uprights 13 (Figs. 1, 2 and 7). Near one end the shaft 17 has a pinion 18 meshing with a gear 19 of a shaft 20, the latter having a pinion 21 meshing with a gear 22 of the shaft 23 which latter carries 60 a plurality of marking wheels 24 which may vary in number according to the preferred width and capacity of the machine. The drawings illustrate four marking wheels 24, but some of the machines constructed according to the present invention have 65 considerably more marking wheels and cooperating article-feeding units. The periphery of each wheel 24, which is of metal, is roughened, preferably by transverse corrugations, and carries a plurality of printing dies 25 which, in practice, are changeable to meet requirements as to the particular markings desired.

The shaft 20 (Figs. 1 and 2) has a sprocket 26 which is connected by a chain 27 with a 70 lower sprocket hereinafter described, for actuating the mechanism which conveys the articles to position to be acted upon by the printing wheels.

The mechanism for inking the dies 25 by 75 means of a rotating and travelling ribbon will now be described.

The shaft 17, at its other end from the described pinion 18, carries a pinion 28 (Figs. 1 and 7) meshing with the gear 29 of a shaft-like ribbon carrier 30 the hubs 31 of which are mounted to rotate in bearings in the frame uprights 13. Secured to the outer faces of the two hubs 31 are disks 32, 33, the diameters of which are such as to slightly 80 overlap the bearings in the frame uprights, said disks serving to retain the ribbon carrier in proper longitudinal position, and also supporting the ribbon reels as will now be explained.

As best shown by Figure 7, the disk 32 has a bracket 34 having a spindle 35 on which the supply reel 36 for the inking ribbon *a* is mounted, the unwinding of the ribbon from said reel being frictionally retarded by a washer 37 pressed against the side of the reel by a spring 38. Projecting from the disk 33 at the other end of the ribbon-carrier (Figs. 7, 8 and 9) is an arm 39 which carries the 10 step-by-step ribbon-winding-up mechanism which will now be described.

Secured to the outer face of the arm 39 is a casing 40 containing the hub 41 of the shaft 42 for the winding-up reel 43, said shaft 42 15 extending through the arm 39 and rotatable therein. A portion of the hub 41 is formed as a gear 44 having forty one teeth. Between the gear 44 and the inner face of the casing is a gear 45 which is non-rotatable, as by 20 means of a pin locking it to the casing. The gear 45 has forty teeth. Rotatable on the hub 41 is a disk 46 carrying a pinion 47 which meshes with both of the differential gears 44, 45. Secured to the disk 46 and also 25 rotatable on the hub 41 is a ratchet 48 which is engaged by a pawl 49, the latter being carried by a lever 50 mounted on the hub 41 and projecting through an opening 51 in the casing 40 and having a roll 52 at its outer end. 30 A cam 53 (Figs. 7 and 8) is mounted in fixed position with its face in the path of rotation of the lever roll 52 so that each time that the ribbon-carrier 30 and its end reels rotates, the roll 52 will contact once with the cam and the 35 lever 50 will be actuated to cause its pawl 49 to actuate the ratchet 48. Overthrow of the ratchet is prevented by a suitable brake such as a spring-pressed plug 54 (Fig. 9). Since the ratchet is connected to the disk 46 and the latter carries the pinion 47 which meshes 40 with the differential gears 44, 45, the transmission of rotation to the reel 43 to effect feed of the ink ribbon along the rotary carrier 30 is very slow.

As indicated by dotted lines in Figure 7, 45 there are passages for the ribbon *a* through the hubs 31 of the rotary carrier, but between said hubs the ribbon extends along the surface of the carrier, passing (Figs. 2, 7 and 8) 50 over cushions 55 and through guides 56 mounted on the carrier 30, the cushions and guides alternating with each other. The cushions are in such locations, and the relative timing of rotation of the ribbon carrier and the die wheels 24 is such, that when the dies 55 55 are passing the carrier 30 the cushions 55 will press the ribbon *a* against the dies and transfer ink thereto.

The mechanism for transferring the articles, without stopping, to position to be marked, will now be described.

The hereinbefore described chain 27 drives the sprocket 57 of a shaft 58 (Figs. 1 and 2) mounted in hangers 59 (Fig. 6) depending 65 from portions of the frame 12. The said

shaft, incidentally, provides a pivotal support for a series of runways one of which is illustrated alone in Figure 6. In practice there is a pivoted runway in line with each marking wheel 24. Each runway includes an 70 angular member having its hub 60 (Fig. 6) mounted on the shaft 58, one arm 61 extending under a wheel 24 and the other arm 62 extending down and having a spring 63 connected to it to normally hold the runway in 75 about the position illustrated by Figure 2, a cross bar 64 serving as a stop for the several arms 62.

Projecting laterally from the end of each arm 61 is a pin on which a sprocket 65 is idly 80 mounted. Secured to the driven shaft 58, alongside each arm 61 (Figs. 4 and 6) is a sprocket 66. A chain 67 connects each sprocket 66 with a sprocket 65. Each chain 67 carries a series of pushers 68 at predetermined 85 spaced distances apart. The pushers are formed to present forward faces which are so curved or recessed (Figs. 1, 4 and 6) as to retain the spherical articles *b*, whether large or small, with their central or largest diameters in line with the marking dies of the wheels 24. Each pusher 68 is connected to or is a part of a block 69 having pivotal connection with the chain and provided with a rearwardly projecting lug or heel to bear on the chain and ensure proper upright position of the pusher to carry an article *b* up the inclined path of travel. 95

Each arm 61 carries a bracket 71 (Figs. 4 and 6) the upper edge of which is branched 100 to support trough members 72, the chain 67 travelling in the narrow space between the inner edges of said members 72.

Each runway, in its entirety, is so positioned and mounted that during the operation of a pusher 68 it is travelling in an upwardly inclined direction the latter portion of its travel being nearly horizontal due to a small sprocket 73 near the sprocket 65 and over which the chain rides. This is to ensure 110 the action of gravitation to maintain each article resting against a pusher, and not in advance of it, as it approaches the marking wheel. In this connection it is to be understood that the pushers of each runway are so spaced, and the timing is such that the speed of travel of the chains 67 relatively to the speed of rotation of the wheels 24, will ensure the arrival of a pusher 68 in the approximate position illustrated by Figure 4 115 coincidentally with the arrival of a wheel die 25 above it. The peripheral speed of the wheels 24 is sufficiently in excess of the speed of travel of the pushers to cause the roughened surfaces of the wheels to roll the articles away from the pushers while the dies are printing the articles, and to then effect delivery of the marked articles to any suitable receptacle or to a trough one end of which is indicated at 74 in Figure 2. 120

125

130

- The mechanism for delivering the articles to the runways will now be described.
- At the supply end of the machine are two shafts 75, 76 (Fig. 2) the latter being driven by a chain 77 (Fig. 1) connecting a sprocket 78 of the shaft 58 with a sprocket 79 of the shaft 76. The sprocket 78 is much smaller than the sprocket 79 so as to effect a comparatively slow speed of travel to the slatted conveyor platform now to be described.
- Between side guides 80 supported by the frame of the machine are oppositely bevelled transverse slats 81 carried by chains 82 mounted on small sprockets 83 carried by shaft 75 and larger sprockets 84 carried by the driven shaft 76. Guide strips 85 are supported at their outer ends by a cross bar 86 and at their inner ends (illustrated by dotted lines in Figure 2) by a transverse rod 87.
- A flat plate 88 (Figs. 1, 2 and 5), preferably having an upwardly bent edge, extends onto the conveyor platform. It is pivotally mounted on the rod 87 so that it can freely rise and fall as the higher and lower surfaces of the platform strips 81 pass under its edge.
- Articles which are to be marked are delivered by the slatted platform onto the vertically oscillating plate 88 and roll down over said plate to position to be taken individually by the pushers 68 and transferred up under the marking wheels. To properly direct the articles in a straight line when rolling over the plate 88, guides 89 are provided, said guides being connected at their upper ends to the strips 85 and supported by being overlapped thereon.
- The operation of the machine is as follows: The articles, such as citrus fruit, are deposited promiscuously on the slatted conveyor platform. They do not need to be sorted as to sizes. Each article will automatically find its way singly into what may be termed a pocket bounded on two sides by the guide strips 85 and on the other two sides by the oppositely inclined surfaces of the conveyor slats 81.
- It is to be understood here that the timing in speed of travel of the moving parts of the machine, due to the relative sizes of the gears, and chain sprockets, and to the spacing of the pushers and the spacing of the dies carried by the printing wheels, all as indicated in the drawings, is such that the articles (which may completely occupy singly all of the pockets of the conveyor) will be lifted singly out of the pockets by the plate 88, and each will then roll down over said plate and drop into a space between two of the pushers 68. The action of the slats 81, passing under the plate 88, causes the latter to oscillate vertically and practically lift the articles out of the pockets.
- Owing to the upward incline of the runways, each article rolling from the plate 88 will find its way snugly against a pusher 68,
- and centrally thereof due to the reentrant curvature of the pusher and the trough shape of the members 72, and will be carried up under a printing wheel, the latter part of such movement being in a nearly horizontal direction. The timing is such that a portion of the wheel carrying a marking die will roll the article in a nearly horizontal plane away from the pusher which brought it to position, and simultaneously mark it. As will be understood by comparing Figures 2 and 4, practically any size of citrus fruit can be market by the machine, even if smaller ones alternate with large ones, because there is ample space under each wheel 24 at the lower end of the pivoted runway, and the upper portion of said runway yields to any required extent when a pushed article reaches the wheel.
- The slatted conveyor travels continuously, the pusher-carrying chains travel faster and also continuously, and the marking wheels rotate continuously in such timing that the dies 25 will approach position above the yieldable runways just as articles approach the upper ends of the latter. Therefore, since the articles supplied to the slatted platform are subjected to no stoppage at any point through the machine, a very high speed of production of marked articles is effected, whether the articles are of uniform or varying sizes. The machine illustrated has produced marked oranges at the rate of 150 a minute for each of the plurality of feeding and marking units.
- Having now described my invention, I claim:
1. A fruit-marking machine having a wheel provided with a printing die, and said wheel being roughened in peripheral alignment with the die, means for inking the die, and means for supplying fruit to position adjacent to the wheel in time for the fruit to be simultaneously marked by the die and rolled along by the wheel.
  2. A fruit-marking machine having a wheel provided with a plurality of spaced printing dies, and said wheel being peripherally roughened in line with the dies, and means for supplying definitely spaced fruit successively to positions adjacent to the wheel in time for each fruit to be simultaneously marked by one of the dies and rolled along by the wheel.
  3. A marking machine having a die-carrying wheel, means for supplying articles to position to be marked by the die, a rotary ink-ribbon-carrier, and means for rotating said carrier and wheel in time to cause contact of the ribbon with the die.
  4. A marking machine having a wheel provided with a plurality of dies, means for supplying articles successively to position to be marked by the dies, a rotary ink-ribbon-carrier, and means for rotating said carrier and wheel in timed relationship to cause contact

of the ribbon with each of the successively passing dies.

5. A marking machine having a die-carrying wheel, means for supplying articles to position to be marked by the die, a rotary ink-ribbon-carrier, means for rotating said carrier and wheel in time to cause contact of the ribbon with the die, and means for feeding the ribbon lengthwise of the carrier as it rotates.

10 6. A marking machine having a plurality of die-carrying wheels in axial alinement, means for supplying articles to positions to be marked by the dies, a rotary ink-ribbon-carrier having cushions spaced correspondingly with the several die wheels, and means for feeding the ribbon lengthwise of the rotary carrier and over said cushions.

7. A marking machine having a plurality 20 of die-carrying wheels in axial alinement, means for supplying articles to positions to be marked by the dies, a rotary ink-ribbon-carrier having cushions spaced correspondingly with the several die wheels and having 25 ribbon guides alternating with said cushions, and means for feeding the ribbon lengthwise of the rotary carrier over said cushions and through said guides.

8. A marking machine having a die-carrying wheel, and yieldable means for supplying 30 articles to position to be marked by the wheel die, said supplying means comprising a chain mounted to travel in an upwardly inclined direction and having recess-faced pushers, 35 trough-shaped guiding members being mounted at the sides of the path of travel of the pushers.

9. A marking machine having a plurality 40 of die-carrying wheels, and independently yieldable means for supplying articles to position to be marked by the wheel dies, each of said supplying means including a chain having pushers shaped to present recessed 45 operating faces.

45 10. A marking machine having a die-carrying wheel, and yieldable means for supplying articles to position under the wheel to be marked by the wheel die, said supplying means including a chain having pushers with 50 recessed operating faces, said chain being mounted to travel preliminarily in an upwardly inclined direction and in a less inclined direction when passing under the wheel.

55 11. A machine of the character described, having a plurality of marking units and a travelling platform to deliver articles thereto, said platform comprising an endless series of oppositely bevelled transverse slats, and 60 means for limiting lateral movement of articles on said slats.

12. A machine of the character described, 65 having a plurality of marking units and a travelling platform to deliver articles thereto, said platform comprising endless chains hav-

ing oppositely bevelled transverse slats connected thereto, stationary guide bars being located above the slats parallel with the path of travel of the latter.

13. A machine of the character described, 70 having a plurality of marking units and a travelling platform to deliver articles thereto, said platform comprising an endless series of oppositely bevelled transverse slats, means for limiting lateral movement of articles on 75 said slats, and a pivoted plate having its free edge resting on said slats.

14. A high-speed marking machine having a continuously travelling supply platform for the articles to be marked, an upwardly inclined continuously travelling series of pushers to receive the articles from the platform, and a continuously travelling die-carrier for marking articles advanced by said pushers, 80 spaces being provided between the pushers to enable articles to be rolled away from the pushers when acted upon by the carrier.

15. A machine of the character described, 85 having a die-carrying wheel, a yieldably mounted guide-way extending under the wheel, and pushers movable along said guide-way, spaces being provided between the pushers to enable articles to be rolled away from the pushers, along said guide-way, when acted upon by the die-carrying wheel.

In testimony whereof I have affixed my signature.

FREDERICK J. SÉVIGNE.
